CLAIM

The ornamental design for a cable tie, as shown and described.

DESCRIPTION

FIG. 1 is an enlarged top, front, right side perspective view of our new design for a cable tie;

FIG. 2 is an enlarged top plan view thereof;

FIG. 3 is an enlarged bottom plan view thereof;

FIG. 4 is an enlarged front elevation view thereof;

FIG. 5 is an enlarged rear elevation view thereof;

FIG. 6 is an enlarged bottom, front, left side perspective view thereof;

FIG. 7 is an enlarged left side elevation view thereof, the right side view being a mirror image thereof;

FIG. 8 is a top, front, right side perspective view thereof;

FIG. 9 is a top, rear, right side perspective view thereof;

FIG. 10 is a bottom plan view thereof; and,

FIG. 11 is a bottom, front, left side perspective view thereof.

The broken lines depict portions of the cable tie that form no part of the claimed design. The dot-dot-dash broken lines in the drawings define the bounds of the claim and form no part thereof.
